UNITED STATES PATENT OFFICE.

ROBERT MECHAU, OF JENA, GERMANY, ASSIGNOR TO THE FIRM OF CARL ZEISS, OF JENA, GERMANY.

INDICATOR FOR HEAT RAYS.

Application filed August 13, 1921, Serial No. 492,136, and in Germany October 25, 1917.

The present invention relates to indicators for heat rays which are provided with a collective system serving for receiving the rays of heat, in the focal plane of which system 5 a heat-sensitive device is disposed, in which changes of temperature evoke alterations in the intensity of an electric current passing through it. The invention consists in that the said indicators are equipped with a semi-spherical auxiliary mirror the center of curvature of which coincides with the focal point of the collective system, and the opening of which faces this system, and that the receiving surface of the heat-sensitive device is disposed outside the optical axis of the collective system. This manner of construction affords the possibility of uniting a certain number of rays, the existence of which is to be proved, on a receiving surface 10 of the heat-sensitive device which need only be half the size of that hitherto necessary for receiving the same number of rays, in virtue of the fact that the new arrangement permits of a radiation of the heat-sensitive device from two sides, i. e. from the front and from the back. The heat-sensitive devices may thereby consist of thermo-elements, or thermo-piles, or hot wires for bolometric arrangements. 15 If besides the one heat-sensitive device other such devices of the same kind and of approximately the same size are disposed in the focal plane of the collective system, it will be recommended to have the spaces 20 which, of course, have to be left between the individual devices so that rays which leave the collective system may reach the auxiliary mirror, equal to the width of the heat receiving parts of the devices, so as to fully 25 utilize the rays emerging from the collective system.

The annexed drawing shows a constructional example of an appliance according to the invention, in the focal plane of which 30 there are disposed two thermo-elements. Fig. 1 is a section perpendicular to the optical axis of the collective system on line 1—1 of Fig. 2. Fig. 2 is partly a side-view,

and partly a section in the direction of the optical axis of the collective system. 50

The appliance is equipped with a concave mirror *b*, which is disposed in a casing *a*, and serves for collecting the rays the existence of which is to be proved. This mirror is faced by a small semi-spherical auxiliary 55 mirror *c*, the optical axis X—X of which coincides with the axis of the concave mirror *b*. Between the two mirrors, in the focal plane of the mirror *b*, two thermo-elements are disposed, which consist each of an iron 60 wire *d* to which a constantan plane *e* is soldered, the iron wire of one element being connected to a metal clip *f*, and the constantan plate of the other element to a metal body *g*, while the iron wire of the 65 second element and the constantan plate of the first are connected to a common metal clip *h*, in which manner the two elements are connected in series; besides, the metal clip *f* and the metal body *g* are connected 70 with each other through a galvanometer *G*. In this instance the surfaces of the constantan plates *e* having the width *i*, which surfaces appear in Fig. 1 between the iron wires *d*, have to be considered to be the receiving 75 surfaces of the heat-sensitive devices. The distance apart of the two receiving surfaces is equal to the width *i* of these surfaces, in which manner this appliance permits of utilizing a pencil of rays having four times 80 the width of a receiving surface.

I claim:

1. In an indicator for heat rays the combination with a casing having an aperture therein, of a collective optical system fixed 85 relatively to the aperture, a semispherical mirror having a smaller diameter than the said system and being fixed within the said casing, the centre of curvature of this mirror coinciding with the focal point of the 90 said system and its opening facing this system, and a heat sensitive device located in the said casing in the focal plane of the said system, set off from the axis of the same. 95

2. In an indicator for heat rays the com-

bination with a casing having an aperture therein, of a collective optical system fixed relatively to the aperture, a semispherical mirror having a smaller diameter than the 5 said system and being fixed within the said casing, the centre of curvature of this mirror coinciding with the focal point of the said system and its opening facing this sys-

tem, a plurality of heat sensitive devices, all such devices being of approximately the 10 same size and being located in the said casing in the focal plane of the said system, every two such devices having a space between them about equal to the width of the devices.

ROBERT MECHAU.
